UNITED STATES PATENT OFFICE.

WILLIAM B. JASPERT, OF WILKINSBURG, PENNSYLVANIA, ASSIGNOR TO WESTINGHOUSE ELECTRIC & MANUFACTURING COMPANY, A CORPORATION OF PENNSYLVANIA.

ENGINE STARTER.

Application filed November 23, 1922. Serial No. 602,814.

To all whom it may concern:

Be it known that I, WILLIAM B. JASPERT, a citizen of the United States, and a resident of Wilkinsburg, in the county of Allegheny and State of Pennsylvania, have invented a new and useful Improvement in Engine Starters, of which the following is a specification.

My invention relates to engine-starters for motor vehicles and it has particular relation to such mechanisms as automatically control the operative connection between starting motors and internal-combustion engines.

One object of my invention is to provide a starting mechanism of the character described above which shall embody few moving parts of relatively low inertia.

A second object of my invention is to provide a starting mechanism in which the member corresponding to the usual motor pinion is not bodily movable relatively to the engine member.

A further object of my invention is to provide a starting mechanism of relatively few and simple parts for controlling the operative connection of a starting motor to an engine member according as the latter constitutes the driven or the driving member.

Starting mechanisms, as heretofore employed, usually comprised a pinion that was actuated longitudinally of the motor shaft by screw threads or equivalent means to engage the engine member upon the starting of the motor from rest. Such devices have the disadvantages that the moving parts have considerable inertia, whereby the co-acting teeth are damaged in case they do not meet in proper relation and that springs and other parts of the mechanisms are subject to breakage or derangement.

According to the present invention, I employ a motor member in the form of a sprocket-wheel having inclined teeth which coact with the roller members of a link chain that surrounds the sprocket member. The usual engine fly wheel is provided with teeth of the form of the well-known ratchet which are automatically engaged by the roller link chain when the motor is started from rest. When the engine starts under its own power, the roller members of the chain are ac-

tuated into the bottom portions of the recesses of the sprocket wheel, whereby the motor is disconnected from the engine.

In the accompanying drawings,

Figure 1 is a side view, in elevation, of a starting mechanism constructed in accordance with my invention, the engine fly wheel and the starting motor being shown in part only;

Fig. 2 is an end view of a portion of the fly wheel and associated parts, the chain being in its inoperative position;

Fig. 3 is a view similar to Fig. 2 with the parts in operative position;

Fig. 4 is an end view of a modification;

Fig. 5 is a view, similar to Fig. 2 of a modification of the fly wheel teeth, the parts being in inoperative relation;

Fig. 6 is a view of the mechanism of Fig. 5, the parts being in engaging position;

Fig. 7 is a view similar to Fig. 3 of a further modification; and

Fig. 8 is a side view, partially in elevation and partially in section, of the mechanism of Fig. 7.

Referring particularly to the form of my invention illustrated in Figs. 1, 2 and 3, an engine fly wheel 1, only a portion of which is shown, is provided with teeth 2 similar to those of the well-known ratchet, each of which has a relatively steep side and an inclined side. A starting motor 3, which may for example, be an electric motor, has a shaft 4 to which is secured a sprocket wheel 5 having teeth 6 similar to those of the fly wheel 1.

Surrounding the sprocket wheel 5 is a roller link chain 7 having transversely extending rollers 8 which correspond in number to the teeth 6 of the sprocket wheel 5. The rollers are connected by pairs of oppositely disposed link members 9 which hold the rollers 8 in spaced relation and prevent the lateral displacement of the chain with respect to the sprocket wheel. The chain 7 is of such length that each of the rollers 8 may simultaneously engage the outer portion of the inclined side of the corresponding tooth 6.

When the sprocket wheel 5 is stationary and certain of the rollers 8 occupy the lower portions of the recesses between the sprocket teeth 6, certain other rollers are not in engage-

ment with the sprocket wheel, as is illustrated in Fig. 2. When, however, the motor 3 is operated, the inertia of the chain 7 is such that the sprocket wheel 5 rotates in a 5 counter-clockwise direction relatively to the chain, and the latter assumes the position in which it is illustrated in Fig. 3. The clearance between the teeth 6 and the teeth 2 of the fly wheel is such that the rollers 8 are 10 caused to engage the teeth 2 and thereby establish an operative connection between the motor and the engine.

When the engine starts, the fly wheel 1 is actuated in the direction of the arrow at such 15 speed that the teeth 2 travel much faster than the teeth 6 and the chain 7. The rollers 8 of the chain are accordingly actuated into the deeper portions of the recesses between the sprocket teeth, and the driving connection 20 between the fly wheel and the motor is broken. In case succeeding rollers 8 should happen to be in operative positions when they are adjacent to the fly wheel 1, the teeth 2 actuate them into the lower portions of the 25 corresponding recesses and no operative connection is established. The motor comes to rest when its circuit is opened by the operator.

Reference may now be had to Fig. 4, which 30 illustrates a modification. In this structure, the fly-wheel teeth 10, which are similar to those illustrated in Figs. 1, 2 and 3, are located on the inner periphery of an annular flange 11 of the fly wheel. Since the operation of the mechanism is similar to that of the structure previously described, no description thereof is necessary.

The mechanism shown in Figs. 5 and 6 40 differs from the mechanism of Figs. 1, 2 and 3 only in that the fly-wheel is provided with teeth of different form and number. The teeth 12, which are double in number, as compared with the teeth 2, are symmetrical in form and are substantially sinusoidal in 45 shape. The increased number of teeth facilitates the engagement of the rollers 8 of the chain since the number of points that may be engaged thereby is correspondingly greater. This modification possesses the advantage, also, that the teeth may be formed more easily and conveniently than the teeth 2 of the structure previously described.

In the mechanism shown in Figs. 7 and 8, 55 the fly-wheel gear teeth 14 are of conventional form and the chain 15 may be similar to the well-known Morse silent chain of the rocker type. The chain 15 is provided with inwardly-extending lugs 16, which coact with the recesses of the sprocket wheel 5 in a manner similar to that described in connection 60 with the rollers 8 of the chain 7. The chain 15 is also provided with inwardly-extending plates 17 which coact with circumferential grooves 18 to prevent lateral displacement of 65 the chain. Since the operation of this mech-

anism is substantially identical with that of the mechanisms previously described, extended description thereof is unnecessary.

The advantages of a starting mechanism constructed in accordance with my invention are that no relative bodily movement between the engine fly wheel and the motor-driven member is required and the flexible chain on the motor-driven member effects the operative connection and disconnection of these parts with a minimum amount of rotative movement of the motor. The parts engage with little or no shock by reason of the fact that such engagement occurs upon the initial rotation of the motor. The fly-wheel teeth are not damaged by continued use of the starting mechanism by reason of the fact that the operative connection is always established with the entire tooth rather than an end portion, as may be the case with the usual starting mechanism.

The arrangement whereby the sprocket wheel is always in the plane of the fly wheel permits the use of a very short motor shaft which may be rigidly mounted. The few parts of my starting mechanism may be of such simple and rugged character as to have long life and be free from such damage as may cause frequent repair or replacement. It will be readily understood that the chain is not placed under any considerable stress, since the force of the motor is transmitted to the fly wheel directly between the co-acting teeth by means of the rollers of the chain.

I claim as my invention:

1. An engine starter comprising a rotatable member having inclined surfaces thereon and a flexible chain having members movable outwardly on said surfaces beyond the periphery of said member when the latter is rotated.

2. An engine starter comprising a member having inclined recesses in its outer periphery, and a roller link chain surrounding said member and having members movable outwardly in said inclined recesses when the member is rotated.

3. In a starting mechanism, an engine member and a motor member in the same plane, said members having spaced axes and spaced peripheries, and means carried by the motor member and substantially coaxial therewith for engaging the engine member upon the rotation of the former.

4. In a starting mechanism, an engine member and a motor member in the same plane, said members having spaced axes and spaced peripheries, and flexible means for automatically connecting said members upon the rotation of said motor member.

5. In a starting mechanism, an engine member and a motor member in the same plane, said members having spaced axes, and spaced peripheries, and means comprising a

flexible chain for automatically connecting said members when the peripheral speed of the motor member exceeds that of the engine member.

5 6. In a starting mechanism, the combination with an engine member having a recessed surface, a motor member in the plane of said surface and means comprising a flexible chain that is controlled in accordance 10 with the speed of said motor member for engaging said recessed surface.

7. In a starting mechanism, the combination with an engine member having a recessed surface, a motor member in the plane 15 of said surface and normally disconnected from said engine member and a flexible chain carried by said motor member for engaging said recessed surface upon the rotation of the motor member.

20 8. In a starting mechanism, the combination with an engine member having a recessed surface, a motor member in the plane of said surface and having inclined recesses 25 in its periphery and a flexible chain carried

disposed in said inclined recesses, said chain being of such length that said elements move outwardly in said recesses to engage said recessed surface when the motor member is actuated from rest.

30 9. In a starting mechanism, the combination with an engine flywheel having a recessed surface and a motor-actuated member in the plane of said flywheel, said member being permanently spaced from said flywheel and having inclined surfaces in its periphery, of a flexible chain carried by said motor member having elements coating with said inclined surfaces to move outwardly thereon to engage the recessed surface of 35 said flywheel when said member is started from rest and to move inwardly thereon when the peripheral speed of the flywheel exceeds that of the motor member to disconnect the motor member from the flywheel.

40 In testimony whereof, I have hereunto subscribed my name this 30th day of October, 1922.

45 WILLIAM B. JASPERT.
